PHOTOGRAPHIC FLASH UNIT

Bert A. Ferman, Denver, Colo., assignor to Minneapolis-Honeywell Regulator Company, Minneapolis, Minn., a corporation of Delaware

Application December 5, 1957, Serial No. 48,791

Term of patent 7 years

(Cl. D61—1)

Fig. 1

Fig. 2

Figure 1 is a front perspective view of the photographic flash unit, as seen from above and to the right; and

Figure 2 is a front perspective view of the photographic flash unit, as seen from below and to the left.

The rear, not shown, is conventional. Portions of the drawing figures are diagonally lined to indicate transparency. The dominant features of my new design are shown in solid lines in the drawing.

I claim:

The ornamental design of a photographic flash unit, substantially as shown and described.
